UNITED STATES PATENT OFFICE

FRANK G. BROTH, OF KOHLER, WISCONSIN, ASSIGNOR TO KOHLER COMPANY, OF KOHLER, WISCONSIN, A CORPORATION OF WISCONSIN

CLOSET SEAT HINGE

Application filed November 25, 1929. Serial No. 409,560.

The invention relates to closet seat hinges.

An object of the invention is to provide a simple but effective closet seat hinge including a pair of hinge members which are securely and rigidly attached to opposite side edges of the seat member to prevent weaving of the parts and to permit expeditious further tightening in the event of shrinkage of the seat member.

10 Another object of the invention is to provide an adjustable friction between the parts by which the cover may be made to remain at any desired angle without falling, thus avoiding slamming of the cover and also permitting the cover to stand at an angle less than 90° from its horizontal position in cases where the flush tank extends over the closet bowl more than the usual distance.

A further object of the invention is to provide the hinge with self-contained stop means which will limit the rearward movement of the cover.

20 A further object of the invention is to construct the hinge in a manner which will permit convenient assembly of the parts and facilitate cleaning.

The invention further consists in the several features hereinafter set forth and more particularly defined by the annexed claims.

30 In the accompanying drawings,

Fig. 1 is a side elevation of a closet seat assembly embodying the hinge of this invention;

Fig. 2 is a detail sectional view taken along the line 2—2 of Fig. 1;

Fig. 3 is a detail sectional view taken along the line 3—3 of Fig. 1;

Fig. 4 is a detail sectional view, similar to Fig. 3, of a closet seat assembly including a modified form of cover mounting;

Fig. 5 is a fragmentary sectional elevation of the closet seat assembly of Fig. 4, taken generally along the line 5—5 of Fig. 4, and

Fig. 6 is a fragmentary detail view of one of the hinge posts or standards.

In these drawings, the numeral 10 designates a closet bowl having apertures at its rear portions receiving therein a pair of spaced upstanding posts or standards 11 secured in place by nuts 12, the usual rubber

washers 13 being provided. The upper ball-shaped ends of the posts or standards are provided with laterally opening bores having journaled therein the opposite ends of a horizontal shaft or pin 14 which extends fixedly through the rear portion of a seat member 15.

In that form of the invention shown in Figs. 1 to 3, a cover 16 is arranged above the seat 15 and each has a narrowed rear portion presenting parallel side cheeks. A pair of angular hinge plates 17 have their lower portions disposed between the opposite side cheeks of the seat 15 and the adjacent posts 11, and are apertured to pivotally surround the shaft 14, there being washers 18 interposed between the hinge plates and the cheeks of the seat. The upper portions of the hinge plates bear against the side cheeks of the cover and are each provided with a pair of spaced lugs 19, which enter and closely fit within bores 20 formed in the cover. A bore 21 is formed in each hinge plate between the lugs 19 and registers with a horizontal bore 22 of the same diameter formed through the rear portions of the cover between its opposite side cheeks. A rod 23 of smaller diameter than the bore 22 extends longitudinally within the bore and has its opposite ends screwed into internally threaded bushings 24 which fit closely within the bores 21 in the hinge plates and in the opposite ends of the registering bore 22 in the cover. The outer ends of the bushings 24 are provided with polygonal heads 25 which engage the outer faces of the hinge plates for 70 clamping the hinge plates into firm engagement with the side cheeks of the cover, thus avoiding loosening of the hinge plates and wobbling or weaving of the cover.

75 In that form of the invention shown in Figs. 4 and 5, angular hinge plates 17', similar to the hinge plates 17, are apertured to receive a pair of parallel rods 23' passing through bores 22' in the rear portion of a cover 16'. Each rod is headed at one end and 80 at its other end is adjustably screwed into an internally threaded bushing 24', which fits closely within one of a pair of bores 21' in one of the hinge plates, the bushing being provided with a slotted head 25'. By turning

the bushings 24' the hinge plates are adjustably clamped into firm engagement with the side cheeks of the cover.

The hinge plates 17 and 17' are each provided at their rear portions with lugs 26, which are adapted to engage sloping stop abutments or shoulders 27 on the hinge posts 11 for limiting the rearward movement of the hinge plates and the attached cover, as seen in Fig. 5, the cover in its rearward position being approximately vertical. By this means the cover is limited in its rearward movement without requiring its engagement with the flush tank, thus avoiding knocking of the cover against the tank and possible marring of the finished surfaces of the parts.

If the material of the cover should shrink for any reason the bushings 24 can be readily turned to restore the clamping engagement. The rod 23 not only serves to clamp the hinge plates against the opposite side faces of the cover but also re-enforces the cover. If desired, one of the bushings may be made fixed to or integral with one of the hinge plates and the rod 23 may be fixed to or integral with one of the bushings. In a similar manner the clamping engagement of the hinge plates 17' with the cover may be restored by turning the bushings 24'.

The adjustable mounting of the hinge plates 17 (and 17') brings them into frictional-engagement with the washers 18 interposed between the hinge plates and the side cheeks 15 of the seat extension, and this adjustable friction is relied on to retain the cover in any angular position without danger of slamming. The life of the hinge is thus lengthened and the cover is permitted to stand at an angle less than 90° from its horizontal position. The latter feature is desirable when the flush tank extends over the bowl more than the usual distance, which would prevent the cover from traveling to its vertical position.

Since the seat and cover are both pivotally mounted to swing about the same axis the raising or lowering of the seat while the cover is in lifted position will not cause movement of the cover.

Except for the cover stop feature, the parts of the hinge may be reversed, that is, those parts that are connected with the seat may be connected with the cover, and those parts that are connected with the cover may be connected with the seat. The terms "seat" and "cover" are, therefore, interchangeable as used in the claims in preference to designating them generically as members.

What I claim as new and desire to secure by Letters Patent is:

60. 1. The combination, with a closet seat and a cover thereabove, of a pair of standards adapted to be secured to a closet bowl, a hinge pin extending between and mounted in said standards and passing through the rear portion of said closet seat, a pair of hinge plates

having their lower portions pivoted on said pin and engageable with opposite side edges of the rear portion of said cover, and means passing through said cover for fixedly clamping said hinge plates to said cover.

2. The combination, with a closet seat and a cover thereabove, of a pair of standards adapted to be secured to a closet bowl, a hinge pin extending between and mounted in said standards and passing through the rear portion of said closet seat, a pair of hinge plates having their lower portions pivoted on said pin and engaged with opposite side edges of the rear portion of said cover, there being a pair of spaced openings formed in each side edge of said cover, a pair of spaced lugs carried on each hinge plate and fitting within said openings, and clamping means for each hinge plate disposed between said spaced lugs on said hinge plate and entering said cover for fixedly clamping said hinge plate thereto.

3. The combination, with a closet seat and cover, of a pair of standards adapted to be secured to the closet bowl, a rod extending between and mounted in said standards and passing through the rear portion of said closet seat, and a pair of hinge members fixedly secured to said cover and having a pivotal mounting about said rod and said hinge members having a frictional connection with the seat for frictionally retarding the movement of said cover to avoid slamming of said cover.

4. The combination, with a closet seat and cover, of a pair of standards adapted to be secured to the closet bowl, a rod extending between and mounted in said standards and passing through the rear portion of said closet seat, a pair of hinge members for said cover having a pivotal mounting about said rod and having a frictional connection with the opposite side edges of the seat for frictionally retarding the movement of said cover to avoid slamming of said cover, and means for adjusting the frictional connection between said hinge members and said seat.

5. The combination, with a closet seat cover, of a pair of hinge plates fixedly secured to the opposite side edges of the cover adjacent its rear portion, supporting means on which said hinge plates are pivotally mounted to permit swinging movement of the cover, means having a frictional engagement with the inner faces of said hinge plates adjacent the pivoted portions of said hinge plates to frictionally retard the movement of said cover, and means for shifting said hinge plates to adjust the frictional retardation of the cover.

6. The combination, with a closet seat member having opposite side edges at its rear portion and a transverse bore extending between said opposite side edges, a pair of hinge plates abutting against said opposite side edges, means passing through said bore for fixedly

clamping said hinge plates to said seat member, there being recesses formed in said side edges in spaced relation to said bore, projecting members carried by said hinge plates and fitting within said recesses for resisting rotation of said hinge plates on said clamping means, and means for pivotally supporting said hinge plates.

5 7. The combination, with a closet seat and a cover, of a pair of standards adapted to be secured to a closet bowl, a hinge pin extending between and mounted in said standards and passing through the rear portion of the seat, a pair of separate hinge plates pivoted on said pin and engaged with the side edges of the cover, and adjustable means passing through the cover for fixedly clamping the hinge plates thereto.

10 8. The combination, with a closet seat and a cover, of a pair of standards adapted to be secured to a closet bowl, a hinge pin extending between and mounted in said standards and passing through the rear portion of the seat, a pair of separate hinge plates pivoted on said pin and engaged with the side edges of the cover, there being an opening extending through the cover, and screw means extending within said opening and operatively connected with the hinge plates for fixedly 15 clamping said hinge plates to the cover.

20 9. The combination, with a closet seat and a cover, of a pair of standards adapted to be secured to a closet bowl, a hinge pin extending between and mounted in said standards and passing through the rear portion of the seat, a pair of separate hinge plates pivoted on said pin and engaged with the side edges of the cover, there being an opening extending through the cover and registering openings formed in the hinge plates, a threaded 25 rod extending within said opening, and attaching means screwed onto opposite ends of said rod and having headed portions engaged with the outer faces of said hinge plates to fixedly clamp said hinge plates to the cover.

30 10. The combination, with a closet seat and a cover, of a pair of standards adapted to be secured to a closet bowl, a hinge pin extending between and mounted in said standards and passing through the rear portion of the seat, a pair of separate hinge plates pivoted on said pin and engaged with the side edges of the cover, there being an 35 opening extending through the cover and registering openings formed in said hinge plates, a threaded rod extending within said opening, and internally threaded bushings screwed onto opposite ends of said rod to 40 fit within said hinge plate openings and having headed portions engaging the outer faces of the hinge plates for fixedly clamping said hinge plates to the cover.

45 11. The combination, with a closet seat and a cover, of a pair of hinge members engageable

50 with opposite side edges of said cover, supporting means on which said hinge members are pivotally mounted, there being a pair of transverse openings extending through said cover between its opposite side edges and arranged one behind the other in spaced relation, and a pair of rods extending through said respective openings and having an operative connection with both of its hinge members for fixedly clamping the hinge 55 members to said cover.

56 In testimony whereof, I affix my signature.
FRANK G. BROTZ.
